UNITED STATES PATENT OFFICE.

SPENCER M. BUMP, OF CLEVELAND, OHIO, ASSIGNOR TO THE BETTCHER STAMPING & MANUFACTURING COMPANY, OF CLEVELAND, OHIO, A CORPORATION OF OHIO.

CHAIR HUB.

Application filed March 9, 1925. Serial No. 14,054.

This invention relates to hubs for chairs, and more particularly to hubs such as are used with revolving chairs. The general object of the invention is to provide an improved construction and arrangement of parts constituting such hub whereby the said parts may be conveniently assembled and supported in assembled position and which will serve, when assembled, to support the inner ends of the legs in an efficient manner.

Further and more limited objects of the invention will appear hereinafter and will be realized in and through the construction and arrangement of parts shown in the drawings wherein Fig. 1 represents a side elevation of the base of a chair of the type referred to and having my hub applied thereto; Fig. 2 a plan view of the hub; Fig. 3 a transverse sectional view through the hub and the inner ends of the legs; Fig. 4 a detail in perspective of one of the hub segments; and Fig. 5 a detail in perspective of the inner end of one of the chair legs. Describing the various parts by reference characters, 1 denotes each of the four legs of a chair, the same being shown as provided with a central tube or sleeve 2 within which the standard (not shown) extends.

For the purpose of clamping the inner ends of the legs and forming a hub for the tube, standard and legs, I provide four pressed-metal hub segments, each having a portion or portions of its sides adapted to bear against the adjacent sides of adjacent legs and each having a projection at each side thereof adapted to enter the recesses in the sides of such adjacent legs, together with a cooperating construction of the segments and of the top and bottom plates of the hub such as will enable the segments, not only to be assembled into a hub, but to be drawn inwardly or toward the axis of the tube by virtue of the assembling operation, thereby causing the legs to be firmly and securely fastened to and between the hub segments.

3 denotes one of the hub segments generally. Each segment is made preferably from sheet metal, which is given the proper shape by means of suitable dies. When the shaping operation is completed, each blank will have assumed the shape shown in the drawings, being provided with a cylindrical

body 4. Projecting from each side of the top and the bottom of said body are radial flanges 5, the said flanges being turned outwardly and being adapted to bear against the sides of the two legs between which the segment is interposed. The central portion of each segment is provided at each edge thereof with an intermediate flange 6, each flange preferably being bent so as to extend at right angles toward the chair leg with which it cooperates. The flanges project circumferentially beyond the flanges 5 and are adapted to enter vertical slots 2^a provided in the faces of the legs 1. Each hub segment is provided, in addition to the flanges 5 and 6, with top and bottom centrally-arranged lugs, shown at 7, 7.

For the purpose of supporting the tube 2 and assembling the hub segments and legs, I employ top and bottom plates which are preferably substantially identical in construction. These plates are indicated generally at 8 and 8^a, respectively, and are preferably approximately circular in outline, having radial projections 8^b, 8^c, respectively. At least one of the plates is provided with slots, indicated generally at 9. The inner wall 9^a of each slot is formed on a curve described from a center eccentric with respect to the axis of the tube 2 and of the hub, whereby the said wall constitutes a spiral which approaches the center of the hub from right to left. The inner portion 9^b of the outer wall of the slot is parallel with the opposite portion of the inner wall, the space between the part 9^b of the outer wall and the opposed part 9^a being approximately equal to the thickness of the metal of which the lugs 7 are composed. At the opposite end, the slot is widened, the outer wall 9^c at this portion of the slot also being preferably concentric with the inner wall but spaced further therefrom than is the part 9^b. The inner end of the wall segment 9^c is connected with the adjacent end of the wall segment 9^b by an inclined segment 9^d.

With the parts constructed and arranged as described, the legs, tube and hub will be assembled as follows:—the legs are positioned about the tube 2 in approximately the manner indicated in Fig. 3, the hub segments are then inserted between the legs, the flanges 6 slipping along the slots 2^a and the flanges 5 bearing against the sides of the legs. The top and bottom plates are then

applied, with the lugs 7 in the widened portions of the slots 9. These plates, and the hub assembly generally, are then held in a suitable jig and the plates are pressed toward each other and rotated in an appropriate direction to cause the lugs 7 to be moved radially inwardly by engagement with the wall segments 9^a and 9^b of the slots. When the plates have been rotated 10 a sufficient distance and the flanges 5 are gripping the legs firmly, the plates are secured to the legs by means of screws 10.

If desired the special slot-construction shown and described herein may be omitted 15 from the bottom plate, the lugs 7 being projected through openings adapted to receive and size the same and being clinched or riveted thereto. The bottom plate is shown as provided with elongated radial 20 arms 8^c having openings 8^d for the screws 10.

By reason of the construction and arrangement of parts set forth herein, I am 25 enabled to provide a hub assembly for the legs of chairs and similar articles, the component members of which assembly may be produced at a comparatively small expense and which, when assembled, will produce a very efficient hub-construction, serving to 30 clamp the legs securely in place.

Having thus described my invention, what I claim is:—

1. A hub construction of the character described comprising a plurality of hub segments each having radially extending edge 35 portions adapted to engage the adjacent side faces of chair legs and edge portions projecting circumferentially beyond such radial projections and adapted to enter slots in the side faces of such legs, and means for securing the said segments in assembled position about the inner ends of such legs.

2. A hub construction of the character described comprising a plurality of hub segments each having a portion of each lateral edge thereof bent radially and an additional portion of each such edge projecting circumferentially beyond such radial projection and adapted to enter a slot in the leg of a chair adjacent thereto, and means for securing the said segments in assembled position about the inner ends of such legs with the circumferential edge portions in slots provided in the side faces of said legs and the radial edge portions engaging such faces adjacent to said slots.

3. A hub construction of the character described comprising a plurality of hub segments each having a portion of each lateral edge thereof bent radially outward and an additional portion of each such edge projecting at an angle to and extending beyond such radial projection and adapted to enter a slot in the leg of a chair adjacent thereto, and means for securing the said segments in assembled position about the inner ends of

such legs with the radial edge portions engaging the side faces of said legs and the other edge portions entering slots provided in the side faces of said legs adjacent to the parts engaged by such radial portions.

4. A hub construction of the character described comprising a plurality of hub segments each having at each lateral edge thereof an upper and a lower radially extending flange and an intermediate flange projecting circumferentially beyond such upper and lower flanges, and means for securing the said segments in assembled position about the inner ends of chair legs with the intermediate flanges seated in slots in said legs.

5. A hub construction of the character described comprising a plurality of hub segments each having at each lateral edge thereof an upper and a lower radially outwardly extending flange and an intermediate flange projecting circumferentially beyond such upper and lower flanges, and means for securing the said segments in assembled position about the inner ends of chair legs with the intermediate flanges seated in recesses in said legs.

6. A hub construction of the character described comprising a plurality of hub segments each having at each lateral edge thereof an upper and a lower radially extending flange and an intermediate flange projecting circumferentially beyond such upper and lower flanges, each segment also having at the top and bottom thereof an integral lug, and top and bottom plates having apertures for the reception of said lugs and adapted to be secured to the inner ends of chair legs.

7. The combination, with angularly disposed chair legs, of hub segments each interposed between the inner ends of adjacent chair legs, a plate to which corresponding ends of the said segments are secured, a second plate, and means for securing the opposite ends of the hub segments to such second plate, the said means comprising lugs carried by the last-mentioned ends of the said segments respectively and slots in the second plate for said lugs, the outer wall of each slot comprising an inner or seating portion and an outer portion spaced from the inner wall a greater distance than the first portion and connected with the said first portion by an inclined wall.

8. The combination, with angularly disposed chair legs, of hub segments each interposed between the inner ends of adjacent chair legs, each segment having edge portions adapted to bear against the sides of the adjacent chair legs, a projection at each edge adapted to enter a seat therefor in the chair leg adjacent thereto, and a lug at the top and at the bottom thereof, a plate to which the lugs at corresponding ends of the said segments are secured, a second plate,

and means for securing the opposite ends of the hub segments to such second plate, the said means comprising lugs carried by such opposite ends of the said segments, respectively, and slots in the second plate for said lugs, the inner wall of each slot being formed on a spiral approaching the center of the hub construction and the outer wall of each slot comprising an inner or seating portion

substantially parallel with the inner wall **10** and an outer portion spaced from the inner wall a greater distance than the first portion and connected with the said first portion by an inclined wall.

In testimony whereof, I hereunto affix my **15** signature.

SPENCER M. BUMP.
